UNITED STATES PATENT OFFICE.

STEPHEN CHURCHIA, OF SPOKANE, WASHINGTON.

TIE-PULLER.

1,247,224.

Specification of Letters Patent. Patented Nov. 20, 1917.

Application filed June 12, 1917. Serial No. 174,250.

To all whom it may concern:

Be it known that I, STEPHEN CHURCHIA, a citizen of the United States, residing at Spokane, in the county of Spokane and State 5 of Washington, have invented certain new and useful Improvements in Tie-Pullers, of which the following is a specification.

My present invention relates to improvements in tie removers under the broad class 10 of pushing and pulling devices, and the invention is designed for the special purpose of providing an apparatus or appliance whereby railway ties may be removed from the road bed with facility, without the usual 15 accompaniment of time and labor expended in removing the material from around the ties.

The invention consists in certain novel combinations and arrangements of parts as 20 will be hereinafter more fully described and claimed.

In the accompanying drawings I have illustrated one complete example of the physical embodiment of my invention constructed according to the best mode I have so far devised for the practical application 25 of the principles of my invention.

Figure 1 is a side elevation of my tie remover showing its position in full lines 30 before manipulation, and showing its position in dotted lines at the end of the stroke required to operate the device.

Fig. 2 is a plan view of part of the device looking down, on line II—II Fig. 1.

Fig. 3 is a sectional view on line III—III in Fig. 1.

In the preferred embodiment of my invention as shown in the drawings, the device is to be manipulated to withdraw the tie 1 from beneath its rails as 2, and to facilitate the operation of the device it may be necessary, in many instances, to loosen the tie from its bed, and also to dig the earth or material from along the upper edges of the 45 tie, but as the time and labor employed in this operation is comparatively slight, its necessity does not affect the efficiency of the appliance.

One of the essential elements of the 50 device is the lazy tongs construction comprising the pivoted, crossed bars 3 and 4, the pivot joint being indicated at 5. The bars are adapted to lie or float upon the top of the tie and each bar is provided with a pair 55 of sharpened spurs 6, 6, 7, 7, which are rigidly fastened to the bars and extend out-

wardly and bent inwardly and downwardly therefrom so that they may engage the sides of the tie to be removed, as indicated in Fig. 2. The two links 8, 8, are pivoted to the bars 60 of the tongs and to each other, and their common pivot point is also utilized for attachment to the eye bolt 9 in the lower end of the operating handle 10 of the device.

The operating handle or lever is ful- 65 crumed against the rail of the track, and to this end I employ a lever arm 11 pivoted at 12 to a shank 13 fixed by the bolt end 14 and nut 15 to the lever, and braced by means of the rigid arm 16. The lever arm may 70 be anchored to the rail by means of the bent metallic plate 17 and the pin or bolt 18, the plate being pivoted at 19 at the end of the plate. The plate is bent to conform to the outline of the rail and is fitted about the 75 head of the rail, and the pin is passed through an opening in the plate, so that the plate is securely attached to the rail and forms a rigid anchor for the fulcrum point of the lever and lever arm. 80

In operating the device, assuming the parts to be as shown in full lines Fig. 1, pressure is brought to bear upon the operating lever and it is forced downwardly and the end with the eye bolt is swung quickly 85 away from the rail. This quick initial movement draws on the links 8, 8 and lazy tongs causing the spurs 6, 6 and 7, 7 to impinge against and to enter the wooden tie, thus grasping the tie at each side thereof, and 90 the continued, but slower and more powerful movement of the lever draws the tie from under the rails and withdraws it from its bed. The end of the stroke of the lever is indicated in dotted lines in Fig. 1, and 95 the distance of travel of the tie is indicated by the distance between the eye bolt 9 in full lines and the same eye bolt indicated in dotted lines. After the down stroke of the lever it is lifted or raised which action 100 disengages the spurs from the tie and at the same time moves them back toward the rail for another grip, and the successive strokes of the lever cause the tie to be moved out until it is in position to be hauled out 105 by the use of picks as usual, for final disposition.

What I claim is:—

1. A railway tie remover comprising in combination a lazy tongs fashioned with 110 crossed bars having parallel free ends formed with spurs engaging opposite sides

of a tie, an operating lever having pivotal, linked connection with said tongs, and a lever arm pivoted to said lever and adapted to engage against a rail as a fulcrum point, whereby the tie is grasped and pulled from its position.

2. In a tie puller, the combination with the crossed pivoted bars having parallel ends and oppositely disposed spurs on said ends, 10 of an operating lever having pivotal con-

nection to said bars, a shank depending from the lever, and a lever arm pivoted in said shank and adapted to engage a stationary member to form a fulcrum, whereby the initial movement of the lever causes the 15 spurs to engage the tie and continued movement causes the bars to pull the tie.

In testimony whereof I affix my signature.

STEPHEN CHURCHIA.
